UNITED STATES PATENT OFFICE.

STEFAN KNYSZ, OF HAMTRAMCK, MICHIGAN.

CAN-OPENER.

1,231,746.

Specification of Letters Patent.

Patented July 3, 1917.

Application filed November 18, 1916. Serial No. 132,100.

To all whom it may concern:

Be it known that I, STEFAN KNYSZ, a subject of the Emperor of Austria, residing at Hamtramck, in the county of Wayne and 5 State of Michigan, have invented certain new and useful Improvements in Can-Openers, of which the following is a specification.

This invention relates to certain new and 10 useful improvements in can openers.

The primary object of the invention is the provision of a unity implement designed for use as a can opener, the arrangement being such as to facilitate the metal cutting 15 operation, whereby a complete circular cut may be readily made when desired.

A further object of the device is to arrange a hand operated tool for cutting annularly upon the circular end of a metallic 20 can, provision being made for engaging the edge of the can for leverage purposes and also to engage at both sides of the severed metal affording a more perfect cutting operation.

25 A still further object of the invention is the provision of an implement capable of removing crimped caps from bottles and metallic coverings from jars as well as cutting open the ends of metallic cans.

30 In the drawings forming a part of this application and in which like-designating characters refer to corresponding parts throughout the several views.

Figure 1 is a perspective view of the 35 device,

Fig. 2 is a bottom plan view thereof with the cork-screw closed,

Fig. 3 is an elevational view of a portion 40 of a metal can showing the device in the opening operation, parts being broken away,

Fig. 4 is a side view of a jar showing the device in the act of removing the cover, and

45 Fig. 5 is a similar view of a portion of a bottle showing the cap being removed by the device.

Referring more in detail to the drawing, a metal handle 10 is provided of general loop-shape, preferably formed of flattened sheet metal, and arranged with its two ends 50 arranged parallel, forming a terminal mounting end 11.

One of the ends of the metal forming the handle 10 is extended, forming a right-angle foot 12 with a concave inner edge 13.

55 A cutting member is carried by the mounting end 11, consisting of a block 14 secured

by rivets 15 between the side portions of the said end 11 and having a pointed cutting plate 16, projecting substantially perpendicularly from the block 14 in the general 60 direction of the foot 12, and having a sharp cutting edge 17 upon its inner side.

By grasping the handle 10 the plate 16 may be forced through the top disk 18 of a can such as 19 at a point adjacent the annular edge thereof and with the concave edge 13 overlying the periphery of the can. The plate 16 is then forced along through the top or end 18 cutting the same in the desired manner, while a cylindrical guard 20 secured 70 to the rear corner of the block 14 at right-angles to the latter rests upon the top 18 at opposite sides of the severed metal. The guard 20 facilitates the cutting of the plate 16, by riding upon the periphery of the can 75 end 18 at one end of the guard while the opposite end thereof engages the portion of the end 18 which has been severed and by preventing the severed portion from bending outwardly adjacent to the plate 16 an 80 entire circle may be cut in the end 18 of the can.

A short claw 21 is secured between the sides of the mounting end 11 at a point opposite the block 14 and having the hooked 85 end 22 extended toward the block 14. The said claw being adapted to engage beneath a crimped cap such as shown at 23 upon the bottle 24 for readily removing the cap. During the cap removing operation the 90 mounting end 11 is positioned upon the cap 23 and the handle 10 employed to force the cap loose. A cork-screw 25 is pivoted as at 26 between the sides of the mounting end 11, the same being readily foldable between the 95 sides thereof as shown in Figs. 2 and 3 of the drawing.

The handle 10 has oppositely arranged claws 27 extending in an opposite direction from the claw 21, adapted to fit beneath a 100 cover 28 of a receptacle such as the jar 29, shown in Fig. 4, for removing the cover therefrom. The cross-bowed end 30 of the handle 10 rests upon the cover 28 during the removing operation, as illustrated in Fig. 4. 105

The complete operation of the device will be apparent from this detailed description thereof, the implement being readily employed for opening the can 19 by cutting the end 18 thereof as shown in Fig. 3 and also 110 for removing a bottle cap and a jar cover, as shown in Figs. 5 and 4, respectively, while

the cork-screw 25 may be readily opened for use and then closed at the will of the operator.

What I claim as new is:—

- 5 A tool of the type described, including a handle-portion formed of a continuous metal-piece in loop formation, with the resultant lateral members thereof terminating in parallel relation, one of the parallel terminals being extended beyond the other, said extension itself having a right angled portion, the angular portion thereof having an inwardly presented concave edge, said par-
- 10

allel terminal portions having secured therebetween, the right-angled shank portion of a 15 tapering blade, the latter being spaced from said terminal-extension and extending in a general direction toward the angular portion of said terminal extension and in a plane parallel with the latter but laterally thereof, 20 the heel of said blade having extending laterally therefrom a cross-piece adapted to form a rest therefor upon the edge of the object being operated upon.

In testimony whereof I affix my signature. 25

STEFAN KNYSZ.
